UNITED STATES PATENT OFFICE.

EDGAR F. VAUGHN AND CHRISTIAN STATES, OF TOPEKA, KANSAS.

FLAMBEAU.

SPECIFICATION forming part of Letters Patent No. 365,234, dated June 21, 1887.

Application filed December 14, 1886. Serial No. 221,499. (No model.)

To all whom it may concern:

Be it known that we, EDGAR F. VAUGHN and CHRISTIAN STATES, citizens of the United States, residing at Topeka, in the county of 5 Shawnee and State of Kansas, have invented certain new and useful Improvements in Flambeaus; and we do declare the following to be a full, clear, and exact description of the invention, such as will enable others skilled in 10 the art to which it appertains to make and use the same.

This invention has relation to improvements in flambeaus; and it consists in the construction, novel arrangement, and adaptation of devices, 15 as will be hereinafter more fully set forth, and particularly pointed out in the claims appended.

The object of our invention is to improve a flambeau, in which the objectionable use of 20 valves might be dispensed with, to render a more perfect combustion by an arrangement of flues or draft-tubes, and to avoid the permeation of the oil into the lycopodium-chamber and its passages, and also to prevent the 25 entrance of the lycopodium back into the blow-pipe. These objects we accomplish by the means shown and illustrated in the accompanying drawings, in which—

Figure 1 is a representation of a longitudinal central section of our improved flambeau. 30 Fig. 2 is a perspective view of the same. Fig. 3 is a cross-sectional view of the oil-chamber, showing the lycopodium-tube and surrounding chamber.

Referring by letter to the accompanying drawings, A indicates the staff or handle, which is of a tubular form. To the upper end of this hollow staff is secured the lycopodium-chamber A', which may be of any suitable 40 shape, and preferably of an approximately hemispherical form, with its flat side uppermost. This lycopodium-chamber is provided with a central vertical aperture in its upper wall, and this aperture is provided with an externally-threaded lip, a, which is designed to engage an internally-threaded lip on the bottom of the oil-chamber when the same are to be connected, as will be hereinafter more fully described.

B indicates a blow-tube, which extends at a suitable point from the hollow handle, and is provided with a mouth-piece, b, as shown.

The opposite end of this tube is closed and passes vertically through the lycopodium-chamber to the base of the threaded lip a. 55 This tube is also provided, near its upper end, with a series of lateral perforations, which are covered with wire-gauze, as shown, so as to prevent the return of the lycopodium, and also the entrance of moisture to the said tube and into 60 the lycopodium-chamber. This tube B is surrounded within the lycopodium-chamber by a tube, C, which is also closed at its upper end, and provided at its base with lateral perforations having a gauze covering similar 65 to that at the upper end of the blow-tube. It will be observed that while these two tubes B C extend to the top of the lycopodium-chamber, yet they do not close the aperture therein, but have a surrounding passage, d, for 70 the egress of the lycopodium or other inflammable powder. Thus it will be seen that when air is blown in at the mouth-piece into the tube B it will pass out through the gauze-covered apertures at the upper portion of the 75 said tube, and before entering the lycopodium-chamber must descend within the surrounding tube C, thereby preventing the accidental entrance of the inflammable powder into the blow-tube and mouth of the operator while 80 breathing inward.

E indicates the oil-chamber, which is arranged above the lycopodium-chamber, and is provided with the filling-aperture C', having a threaded cap, as shown. This chamber 85 is provided with the obliquely-directed wick-tubes e e e, extending from the upper wall thereof, and a central vertically lycopodium-tube, F, which is of less height than the wick-tubes and communicates at its lower end by means 90 of the passage d' with the lycopodium-chamber. This lycopodium-tube in the oil-chamber is surrounded by a tube, G, which has communication with the open air, as will be presently explained. This surrounding tube G 95 has a twofold function. It first serves to prevent the sweat from the oil in the chamber E from permeating into the lycopodium-chamber A', and also as a central draft to feed the flame at the concentric wick-tubes. 100

Between the adjacent sides of the oil and lycopodium chambers is an interspace, H, which is formed by interposing stays between the said chambers. These stays are preferably

of ring form, so as to afford no obstruction to the inlet of air, and are preferably secured to one of the said chambers and bear against the other at its marginal portion. Thus it will be seen that air may freely enter between the two chambers and pass up through the tube surrounding the lycopodium-tube; and we attach importance to this construction, and also to the employment of the tube surrounding the blow-pipe, as it will be readily perceived that sweat or moisture which might permeate the walls of these chambers will be taken up by the passage of air around them, thereby preventing the contact of such with the lycopodium-chamber or any of its attachments.

I indicates a deflector plate or shield, which is arranged around the wick-tubes, and also around the lycopodium and draft tubes, as shown. The threaded lip K, at the base of the oil-chamber, serves through the medium of the lip a to form a connection between the oil and lycopodium chambers. The lower end of the staff is also provided with a stopper or cap to form a sweat trap and a means for the ready removal of the condensed moisture of the breath.

The operation is as follows: The chamber A having been filled with lycopodium or other inflammable powder, and the upper chamber 30 with kerosene or the like, the wicks are properly adjusted in their tubes and the two chambers united by the threaded lips or a can-screw. The wicks are then lighted and the mouth-piece placed to the lips. A smart blast 35 blown in at this point will carry the air to the top of the blow-tube, where it passes out through the lateral gauze-covered apertures into the surrounding annular chamber, and out through the lower lateral apertures of the latter 40 into the lycopodium-chamber, when it takes the course indicated by the arrows, carrying a sufficient quantity of the lycopodium up through the central communicating tube in the oil-chamber and discharges the same into 45 the flame at the desired point.

In some cases it is desirable, and in many cases preferable, to omit the blow-tube from the base of the lycopodium-chamber to the inner end of the mouth branch, thus using the hollow staff for a blow-pipe. This construction is fully shown in Fig. 1 of the drawings.

Having described this invention, what we claim, and desire to secure by Letters Patent, is—

1. The combination of an oil-chamber and a lycopodium-chamber separated by an air-space, the lycopodium-chamber being provided with air-tubes, a tube passing through the oil-chamber and communicating with the last-named tubes, and being surrounded by an air-space within the oil-chamber, substantially as specified.

2. The combination of an oil-chamber and a lycopodium-chamber separated by an air-space, the lycopodium-chamber being provided with air-tubes, a tube passing through the oil-chamber and communicating with the last-named tubes, and being surrounded by an air-space within the oil-chamber, and the burner-tubes, substantially as specified.

3. The combination of an oil-chamber and a lycopodium-chamber separated by an air-space, the lycopodium-chamber provided with air-tubes, a tube passing through the oil-chamber and communicating with the last-named tubes, and being surrounded by an air-space within the oil-chamber, the handle with the air-passage communicating with the air-tubes in the lycopodium-chamber, and the burner-tubes, substantially as specified.

In testimony whereof I affix my signature in presence of two witnesses.

EDGAR F. VAUGHN.
CHRISTIAN STATES.
